UNITED STATES PATENT OFFICE.

VALENTINE MOESLEIN, OF NEW YORK, N. Y.

CONSTRUCTION OF FLOORS, PARTITIONS, OR THE LIKE.

SPECIFICATION forming part of Letters Patent No. 680,062, dated August 6, 1901.

Application filed January 25, 1901. Serial No. 44,709. (No model.)

To all whom it may concern:

Be it known that I, VALENTINE MOESLEIN, a citizen of the United States, and a resident of the city of New York, borough of Manhattan, in the county and State of New York, have invented certain new and useful Improvements in the Construction of Floors, Partitions, or the Like, of which the following is a full, clear, and exact description.

10 The invention relates to fireproof structures; and its object is to provide certain new and useful improvements in the construction of floors, partitions, and the like whereby the floor, partition, &c., can be cheaply constructed and rendered perfectly fireproof.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a longitudinal sectional elevation of the improvement as applied to floors. Fig. 2 is a transverse section of the same. Fig. 3 is a sectional plan view of the improvement as applied to partitions; and Fig. 4 is a 30 cross-section of the improvement, showing a modified form of supporting-iron.

When building a ceiling, the floor-beams A support on their bottom flanges transversely-extending supporting-irons B, preferably in 35 the shape of T or angle irons and placed a suitable distance apart, as is plainly indicated in Fig. 1. These supporting-irons support sheet-metal laths C, arranged lengthwise between adjacent floor-beams and each formed 40 with a plurality of bent-up portions C', adapted to engage and rest on the supporting-irons B, so that each lath is carried by a plurality of supporting-irons, and the bottom portion of each lath is at or below the plane of the bottoms of the floor-beams A, as is plainly indicated in Fig. 2. The ends C² of each lath are bent L-shaped, so that the ends of adjacent laths C overlap, the lowermost end resting on the corresponding supporting-iron B, 45 as is plainly indicated in Fig. 1.

Each metal lath is formed with the usual struck-up portions, and by the arrangement

described the laths C form a support for the concrete or other material D filled in between the floor-beams A to produce a fire- 55 proof floor. The laths C receive on their under surface the usual plaster E, held in position by the struck-up portions of said metal laths C, as is well known.

The laths C are of such a width as to extend between the outer ends of the bottom flanges of adjacent floor-beams A, as indicated in Fig. 2, and in order to have a metal lath extend under the bottoms of the floor-beams I prefer to place a narrow sheet-metal 65 lath C³ on transversely-extending laths C under the bottom flanges of a floor-beam, as is plainly indicated in Fig. 2, so that the entire ceiling can be uniformly plastered, the plaster 70 adhering to the metal laths.

In order to form partitions in a building, I arrange the supporting-irons B' vertically and in pairs, as indicated in Fig. 3, and attach sheet-metal laths C⁴ to said supporting-irons by having the inwardly-bent portions 75 C⁵ of said metal laths C⁴ extend around the supporting-irons, the bent portions being finally crimped upon the flanges of the irons, as indicated in said Fig. 3. The space between the metal laths is preferably filled in 80 with concrete or other material D', but the space may be left empty, if desired; but the plaster E' is placed on the outer faces of the sheet-metal laths, so as to give the desired 85 finish to the partition.

From the foregoing it is evident that the floors and partitions are composed completely of fireproof material, and they can be very cheaply constructed, especially the floors, as no skilled labor whatever is required to place 90 the supporting-irons and the laths in position or to fill in the space between adjacent floor-beams with fireproof material, the latter resting on the laths as a support.

In order to obtain a perfect rest of the supporting-irons on the floor-beams, I prefer to use T-irons B², (see Fig. 4,) having the horizontal member bent down at the ends to rest on the floor-beam flange at the junction with the web of the floor-beam, as shown in Fig. 100 4, the vertical member of the T-iron being cut off at the ends at an angle to allow the bent-down top to rest on the floor-beam flange. By this construction the portions C' of the

metal laths can be made very low, and at the same time a firm resting of the supporting-irons on the floor-beams is insured.

Having thus fully described my invention, 5 I claim as new and desire to secure by Letters Patent—

1. A building structure, comprising spaced supporting-irons, and laths extending transversely of the same from one to the other, 10 said laths having laterally-offset recessed portions passing around the supporting-irons and securing the laths thereto, the recessed portions holding the major portion of the laths at one side of the supporting-irons opposite the side embraced by the said recessed portions, for the purpose specified.

2. A fireproof floor, comprising spaced supporting-irons arranged transversely and resting on the bottom flanges of the floor-beams, 20 and a sheet-metal lath having recessed portions arranged transversely and engaging said supporting-irons, to form a support for the filling-in material between the floor-beams and the support for the plaster, as set 25 forth.

3. A fireproof floor, comprising floor-beams, spaced T-irons resting on the bottom flanges of adjacent floor-beams, and a sheet-metal lath formed with upwardly-bent portions resting on said supporting-irons, said upwardly-bent portions extending transversely of the lath and being arranged to bring the undersurface of the lath to or below the plane of the floor-beam flanges, as set forth.

4. A fireproof floor having supporting-irons 35 resting on the bottom flanges of adjacent floor-beams, sheet-metal laths extending between the floor-beams and resting on said supporting-irons, said metal laths extending below the bottoms of the floor-beams, and narrow sheet-metal laths extending under the floor-beams and resting on adjacent metal laths, as set forth.

In testimony whereof I have signed my name to this specification in the presence of 45 two subscribing witnesses.

VALENTINE MOESLEIN.
